UNITED STATES PATENT OFFICE.

GUIDO WÜNSCH, OF STEGLITZ, NEAR BERLIN, GERMANY, ASSIGNOR TO ASKANIA-WERKE A.-G. VORMALS CENTRALWERKSTATT-DESSAU UND CARL BAMBERG-FRIEDENAU, OF FRIEDENAU, NEAR BERLIN, GERMANY, A CORPORATION OF GERMANY.

GAS-MIXTURE REGULATOR.

Original application filed February 29, 1924, Serial No. 696,103. Divided and this application filed February 20, 1925. Serial No. 10,716.

To all whom it may concern:

Be it known that I, Guido Wünsch, a citizen of the German Empire, residing at 2 Stindestrasse, Steglitz, near Berlin, Germany, have invented certain new and useful Improvements in or Relating to a Gas-Mixture Regulator, of which the following is a specification.

My application for Letters Patent Serial No. 696,103 of which the present application is a divisional one relates to a process and means for the frictionless transmission of movement from a moving primary element to a secondary element to be moved, which can be utilized in various branches of industry. According to the said invention a very slight movement is transmitted from a primary element, for instance such as is usually automatically effected on the said element by an instrument, to a secondary controlling or setting element or to a servomotor, whereupon the said secondary element or servomotor effects the required operation.

The present invention relates to a practical application of the devices claimed in the said copending application and shows how the said process and means may be used in connection with gas mixture regulators.

The accompanying drawing illustrates diagrammatically a device for regulating gas mixture according to the invention.

The mixture regulator as illustrated is more particularly intended for regulating air and gas mixtures for heating and the like, but also suitable for any other desired purposes. The mixture regulator is in a way a duplication of the gas pressure regulator shown in a copending application Serial No. 10,717, filed Febr. 20, 1925, for U. S. Letters Patent. It comprises a gas supply pipe 15 and an air supply pipe 16. In the latter is mounted a throttle valve 17 which is connected by a rod 18 to the rod of

a piston 19. The piston is movably arranged in a cylinder 20, at the bottom and cover of which open two pipes 21, 22 the two other ends of which are arranged adjacent each other in the manner of a nozzle.

Opposite the ends of the pipes 21 and 22 is arranged a nozzle 23 provided at the end of a pipe 25 pivoted about a pin 24. The pipe 25 is freely rotatable about the pin 24, and

liquid under pressure or compressed gas passes through it. It corresponds to the pipe a or a' of Figures 1-3 of my copending application for Letters Patent Serial No. 696,103. In the gas and air pipes 15 and 16 are inserted throttling rings 26 or 27, and diaphragms 28 and 29 are actuated by the pressure differences at those points. To the diaphragms of the differential pressure devices are connected push rods 30 and 31 respectively. The rod 31 engages with the pipe 25 or is pivoted to the same, whilst the rod 30 connects the diaphragm 28 to a lever 32. Between the lever 32 and the pipe 25 is arranged a slide block 33 mounted on a rod 34 which can be moved by a handle or the like 35 in the axial direction of the rod. The mixture of gas and air passes through the chamber 36 towards the burner.

The working of this device is as follows: As long as the proportion between the pressure of the gas passing through the pipe 15 and that of the air passing through the pipe 16 remain unchanged, and the proportion of mixture is the correct one the device remains in the position shown in the drawing. The nozzle 23 is in the centre above the openings of the pipes 21 and 22 so that the fluid under pressure (it is preferable to use compressed air for the purpose) will flow in equal parts into the pipes 21 and 22 and consequently the pressure at

both sides of the piston 19 will remain the same. When the pressure in the pipe 15 changes for instance becomes greater the gas mixture will get less air. In that case the diaphragm 28 owing to the inserted differential pressure regulators will move to the right. Consequently, the pipe 25 will be turned in the anticlockwise direction about the pin 24 by means of the rod 30, lever 32 and the slide 33, and the nozzle 23 will then be moved further towards the pipe 22, and a greater portion of the compressed air will pass from the nozzle into the pipe 22. Consequently the pressure on the right hand side of the piston 19 will become greater, and the piston will be moved to the left and thus will open to a greater extent the throttle valve 17. In that way the air pressure in the pipe 16 will be increased, and as soon as the correct proportion is again reached, the nozzle 23 of the pipe 25 will be

80

again in the centre between the two pipes 21 and 22, and the piston 19 will remain at a standstill. On the contrary, when the pressure in the pipe 15 sinks, the nozzle 23 will be placed opposite the pipe 21 and thereby will produce a closing of the throttle valve 17.

The setting of the slide 33 is intended to regulate the ratio of transmission between the two diaphragms in order thus to be able to set the proportion to be maintained between the pressures in the pipes 15 and 16, without having to change the throttle rings 26 and 27.

15 I wish it to be understood that I have shown and described merely one example of the invention in connection with a certain system of gas mixture regulators. However it will be evident to those skilled in the art that it may be used also in connection with other kinds of such plants without departing from the spirit of the invention.

Having now particularly described and ascertained the nature of my said invention and in what manner the same is to be performed, I declare that what I claim is:

1. In a gas mixture regulator in combination pressure pipes carrying the gases to be mixed, a further pipe through which flows a medium under pressure, means adapted to move said last mentioned pipe in opposite directions corresponding to the rising or falling pressure in said pressure pipes and means operated by the said medium escaping from said further pipe and adapted to effect the mixture regulation.

2. In a gas mixture regulator in combination pressure pipes carrying the gases to be mixed, a further pipe through which flows a medium under pressure, differential pressure devices adapted to respond to the pressure fluctuations in said pressure pipes and moving said last mentioned pipe in opposite direction corresponding to the rising or falling pressure in said pressure pipes and means operated by the said medium escaping from said further pipe and adapted to effect the mixture regulation.

3. In a gas mixture regulator in combination pressure pipes carrying the gases

to be mixed, a further pipe through which flows a medium under pressure such as a compressed gas, differential pressure devices adapted to respond to the pressure fluctuations in said pressure pipes, diaphragms within said differential pressure devices connected with said last mentioned pipe and adapted to move it in opposite directions corresponding to the rising or falling pressure in said pressure pipes and means operated by the said medium escaping from said further pipe and adapted to effect the mixture regulation.

4. In a gas mixture regulator in combination pressure pipes carrying the gases 65 to be mixed, a further pipe through which flows a medium under pressure, differential pressure devices adapted to respond to the pressure fluctuations in said pressure pipes and moving said last mentioned pipe in 70 opposite directions corresponding to the rising or falling pressure in said pressure pipes, an adjustable device arranged between one differential pressure device and said further pipe adapted to enable the 75 ratio between the pressures to be regulated and means operated by the said medium escaping from said further pipe and adapted to effect the mixture regulation.

5. In a gas mixture regulator in combination pressure pipes carrying the gases to be mixed, a further pipe through which flows a medium under pressure, differential pressure devices adapted to respond to the pressure fluctuations in said pressure pipes and moving said last mentioned pipe in 80 opposite directions corresponding to the rising or falling pressure in said pressure pipes, a pivoted lever connected to the one differential pressure device, a slide adjustable in the longitudinal direction of the said lever and adapted to connect the said lever and said further pipe and means operated by the said medium escaping from said further pipe and adapted to effect the mixture regulation. 85

In testimony whereof I have affixed my signature.

GUIDO WÜNSCH.
